UNITED STATES PATENT OFFICE.

DONALD M. SIMONS, OF OSBORNE, AND FRANK D. BARBOUR, OF PITTSBURGH, PENNSYLVANIA, ASSIGNORS TO STANDARD UNDERGROUND CABLE COMPANY, OF PITTSBURGH, PENNSYLVANIA, A CORPORATION OF PENNSYLVANIA.

JOINT-BUILDING MACHINE.

Application filed August 29, 1925. Serial No. 53,306.

Our invention relates to machinery for applying insulation to cable joints. In applications for Letters Patent of the United States, Serial No. 738,424, filed September 5 18, 1924; Serial No. 743,645, filed October 15, 1924; Serial No. 750,740, filed November 19, 1924; and Serial No. 48,301, filed August 5, 1925, Donald M. Simons, one of the present applicants, has shown and described cable 10 joints which include bodies of insulation formed of sheet material laid in a single wrap and in continuous spiral around the conducting parts. Insulation so characterized and so applied has shown itself to be 15 peculiarly serviceable in making installation of cables adapted to carry currents of very high voltage. The joint is of necessity made in the field, and the insulation which overlies and encases the union of the conductors and so forms part of the joint structure must of necessity be applied in the field. Our present invention, as we have said, lies 20 in a machine for wrapping to place such a web of sheet material. In a joint of the kind suggested, the web so applied may be a hundred feet long or more. If applied manually, as but for our invention it must be applied, a very great deal of time is required, a half day, more or less, to wrap the web to 25 place. With the use of our machine, the wrapping may be done, and with surer success, in a half hour or even less.

In the accompanying drawings Fig. I is a view in side elevation of a wrapping machine in which our invention is embodied; Fig. II is a view of the same machine, in end elevation, as seen from the left, Fig. I; and Fig. III is a view partly in opposite end view and partly in vertical and transverse section, on the plane indicated at III—III, 35 Fig. I. Fig. IV is a view, to larger scale, showing in side elevation an appliance which, organized with the other machine parts, serves to maintain the central body in proper position, while the web of sheet insulating material is, by the operation of the machine, being wrapped upon it. Fig. V is a plan view of the structure shown in Fig. 40 IV. Figs. VI and VII are views (not, as will be understood, to the same scale with Fig. IV) in side elevation and in plan of a certain knife which may advantageously be organized with the other machine parts. Fig. VIII is a view in elevation showing the

cable ends prepared for the reception of 55 the wrap.

A frame 1, conveniently formed of rolled steel channel is borne on suitable supports, such as the tripods 11, for temporary erection in the field. Upon this frame two oppositely placed standards 12 are formed with semi-cylindrical seats 13; and removable blocks 14, provided with complementary semi-cylindrical bearing faces, form with the standards clamps for holding a length 60 of cable securely upon the frame while the machine is in operation upon it. These clamps, it will be understood, engage the cable at either side of the union of conductor ends, upon which union the joint structure is to be built.

A drum formed of opposite heads 6 and connecting rods 61 is rotatably mounted upon the standards 12, coaxially with the cable seats formed by the clamping members 65 already described. To this end, in the machine illustrated, the standards 12 and the blocks 14 are provided with extensions which, when the blocks 14 are in place, present cylindrical bearing surfaces, upon which externally the heads of the drum are immediately mounted. For purposes of assembly, the drum heads 6 may be formed with radially extending spaces, of equal width with the cylindrical bearings, in which fillers 62 70 are removably secured.

The drum heads are toothed peripherally, as shown at 63, and the gear wheels so constituted mesh with pinions 81 borne by a shaft 8 which, journalled in the frame, extends in parallelism with the mounted drum. This shaft may be rotated in any suitable manner. Means for rotating shaft 8 manually, and through shaft 8 the drum, are found in a stub shaft 82 also journalled in frame 1, and provided with a crank 83 and with a bevelled pinion 84 which meshes with a bevelled gear wheel 85 borne by the shaft 8.

The filler pieces 62 of the drum-heads 6 carry rotatably the paper reel. A satisfactory structure is that shown in detail in Fig. I. A spool 64 is rotatably carried upon opposite stub shafts 65, and these stub shafts 65 are mounted in the fillers 62 in such manner that while non-rotatable they are extensible and retractible longitudinally, for the application and removal of the spool, while the assembly continues in other respects un-

disturbed. Thumb nuts 66 control stub shafts 65 in their extension and retraction. The more minute details of structure will be understood by the engineer, without particular illustration.

- The rods 61 serve two purposes. Structurally they secure the heads 6 in spaced relation and constitute with the heads the completed drum. Functionally they define a guideway for the paper, in its advance from the reel to the cable body which is in course of building, and afford friction surfaces, to tighten the web. Referring particularly to Fig. III, the cable body in course of building will be understood to be located within the circle 13. The paper-laden reel is indicated at 64. The path of the advancing web of paper is indicated by the line α , and it will be seen that the paper advancing from the reel winds in and out, beneath one rod 61, over the next, beneath a third, and so on, until at last it reaches its place in the volute upon the work. To anticipate more minute description below, it will be understood that rotation of the drum coaxially around the stationary cable body will effect the automatic unwinding of the web of paper from the reel and the winding of it upon the cable body.
- As indicated in Fig. III, the rods 61 may be adjusted and set in one or another of successive radial positions, indicated by a series of anchorage holes 67 in drum heads 6. The rods may be non-rotatable, or, consisting as shown in Fig. III of sleeves around central stems, they may be idly rotatable. The number of rods 61 may be increased indefinitely, and the length of the sinuous path for the advancing web of paper may be extended to such degree as may be desired circumferentially around the drum, and by radial adjustment of the rods 61 individually, the depth of the sinuosity may be varied. Thus retardation or tension may be increased or diminished upon the advancing web of paper. The reel may be braked in any suitable manner, to resist withdrawal of the web of paper from it, and so to increase tension on the paper as it is in course of being laid in place in the joint. For instance, the stub shafts 65 may be tightened upon the spool to afford braking effect. Additionally, we show particular means to the same end, and these particular means, or their equivalent, may or may not be employed.
- A tension device is shown in Figs. I and III, whose office is to brake the turning of the reel and so to place an additional drag upon the automatic advance of the web of insulation, to the end that, being laid under tension, the applied body of insulation shall be firm and compact and uniform in its structure. Resilient brake members, here shown in the form of fingers 60 extend from a rod 61 which in the assembly lies adjacent

to the paper reel. The rod from which these fingers extend may be provided with any suitable adjustable anchorage against rotation; for example, as shown, the rod is provided with a ratchet 68 engaged by a pawl 69 secured to the drum, as by mounting upon an adjacent rod 61. The ratchet may be shifted manually either way, to increase the spring tension under which the fingers 60 bear tangentially upon the surface of the roll of insulation upon the reel, and to keep the tension up while the roll diminishes in radial depth, or alternately to leave the reel free for removal and replacement.

Figs. IV and V show a device for holding the cable body against bending while the wrapping operation is in progress upon it. Manifestly, it is desirable, in order to have the applied wrap lie firm and compact, that the cable body during the wrapping operation extend without substantial departure from its straight-line position. Accordingly, upon two of the rods 61 not overlaid by the web of paper, the device is mounted. Its position is diagrammatically indicated at 9, Fig. I.

This attachment includes a frame 9, removably clamped to two rods 61. This frame affords swinging support for a pair of arms 91, which extend from a cable-engaging member 92, conveniently of the angular cross-section indicated in Fig. IV. An adjusting screw 93, also mounted in the frame, opposes the swing of member 92 and adjustably defines its position. A cable body is diagrammatically indicated at C in Figs. IV and V, and the course of the web of insulation in its approach to the cable body is in Fig. IV indicated at α . The cable body under treatment will be understood to be supported by the two clamps already described, which may be spaced apart at an interval of three feet, more or less, and the attachment here described serves to hold the reach of cable body between the clamps against lateral displacement when the web of insulation is being automatically coiled upon it under tension.

Two of the rods 61 may carry a cutter, for preparing the cable ends for the reception of the web of insulation. The position of such a cutter is diagrammatically indicated at 10, Fig. I, and the minute structure of a suitable cutter is shown in Figs. VI and VII. A frame 110 is mounted upon a pair of rods 61 and is movable along the rods. In this frame at one end a blade 111 is pivoted, and the frame is further provided with a set-screw 112, to hold the blade at a fixed (and adjustable) point, against swinging back. The frame may be provided with a guide 113 for that end of the blade which is remote from its pivot point.

When two cable ends are brought together, and their bared conductors are united, it is

desirable to prepare the cut-away ends of the bodies of machine-laid insulation and of the lead sheaths, for the reception of the joint insulation. This preparation may indeed be made before the union of the conductors is effected. We preferably, however, unite the bared conductor ends; then mount the united structure in our machine, and then, before applying the wrap of paper, prepare the 10 cable body for its reception.

Fig. VIII indicates the preferred form to which the ends of machine-laid insulation and of lead sheath are brought: from the union *u* the bodies *i* of machine-laid insulation recede in a succession of steps, and the outermost and last step is formed by the lead sheath *s*. When the cable body including two cable ends with bared conductors united has been clamped to place in our machine, adjustment of the knife along rods 61 and of the blade in its frame followed by rotation of the drum will effect a cut, defining the rise of any one of the steps shown in Fig. VIII, whether the cut be through lead 25 or through lead and paper or through paper only. The guide 113 for the blade in the frame may be provided with a stop which may be set in any one of a succession of holes 114, and thus the depth of the successive 30 cuts may by predetermined means be accurately defined.

When the cable body is ready to receive its wrap of insulation the insulation, as will be apparent, must be of proper width and must be so particularly placed in the machine, as to come accurately to and to fill the space prepared for it. For a cable body prepared as shown in Fig. VIII, the web *a* of insulation must be of corresponding width, increasing in a succession of steps. And, similarly, as the rods 61 carry a blade for preparing the cable ends in the manner described either of the rods over which the web *a* of insulation advances from the reel 35 to the cable body may be equipped with blades which shall automatically shear the web of insulation at exactly the desired points to precisely the desired width. And similarly as the blade first described is adjustable along the rods 61, these blades for cutting the web of insulation may be adjustable. Two of these will ordinarily be provided, operative simultaneously on opposite sides of the web. In place of specially provided blades, it is manifest that the operator of the machine may slit the web with a knife-blade as it advances; but a machine-operated cutter is better and we indicate at 40 Fig. I, a pair of blades mounted on a rod 61. It is manifest that by causing the cutters to progress axially as the drum rotates (as well as radially, in the case of cutter 10) the resultant shape of cable end and of web may be tapering, instead of being stepped, as shown in the drawings, the ta-

pered form being the limiting form, as the number of steps increases.

In operation a joint casing is first slipped over one of the cable ends. Then the conductors, protruding sufficiently from the 45 cable ends, are united electrically, as by a sweated-on sleeve *u*, Fig. VIII. The machine is set up and made firm in the horizontal position indicated. The thus far united cable body is then introduced through the 50 radial gaps in the drum heads 6 and brought to place in the seats 13, with the union *u* midway of the length of the machine. The blocks 14 are applied, and the cable body 55 clamped to place. The fillers 62 are brought to place and secured in the drum heads.

Knife 110 is then brought into play, adjusted to position, and its blade set, and the handle 83 turned, to rotate the drum. The initial cut will be through the cable sheath 60 and underlying insulation, and at the proper point. When this initial cut has been made, the cut-away material may be removed. Then, by successive settings and adjustments 65 of the knife the cable ends are cut away in 70 symmetrically succeeding pairs of steps. Thus the cable body is prepared for the reception of the web of insulation, the laying of which is the primary purpose of the machine.

A spool-full of paper or other insulation is brought to place and mounted on stub shafts 65. The forward end of the web of paper is carried in pathway *a* around so many of bars 61 as may have been determined on, and then secured to the cable body. It may be that the smaller spaces around the sweated-on sleeve *u* and between the lowest steps of cut-away insulation are filled with hand-wrapped insulation, to the depth 75 of the first step, or it may be that even these spaces are to be filled in the operation of our machine. In any case the advance end of the web of material is secured to the cable body. The advance end will be carefully cut to exactly the width of the space or spaces to be filled, and the knives 100 will be set to the proper positions. The crank 83 is turned 80 and automatically the web of paper advances, is trimmed and laid upon the cable 85 body. Tension may be increased by turning ratchet 68, and will be increased by such means as the coil of paper on spool 64 decreases in depth. Other means of increasing tension have been indicated. As each space 90 between steps of insulation is filled, knives 100 will be adjusted to new positions and the paper will be cut across from the end of one cut to the beginning of the next.

The web of material wrapped by the machine upon the cable body will ordinarily be paper already impregnated with suitable liquid insulation. Whether the material has so preliminarily been filled or not, the materials will be flushed with such liquid ma- 95

terial at the point where the advancing web meets the cable body.

In such manner all the space between the cut-away ends of machine-laid insulation 5 may be filled. At that point the wrapping may cease and the wrapped-on material may be secured and the joint may then be completed in other manner; or the wrapping may continue and in continuous web and in 10 a single wrap the joint may be built out with insulation. The so enlarged body may carry at the margins of the wrap strips of metal, and these may be laid down in electric continuity with the cut-away ends of the cable 15 sheath, in the manner and for the purposes set forth in the companion application of Simons, mentioned above, filed September 18, 1924, Serial No. 738,424.

When the joint is otherwise completed, the 20 joint casing is slipped to place and secured at its ends to the cable sheath. It then is flushed with liquid insulation. Thus the joint is finished, and stands ready for service.

25 The machine which constitutes the present invention is well adapted for field service, and in its use joints of great electrical strength may be built at unprecedented speed.

30 We claim as our invention:

1. In a joint-building machine for electrical cables the combination of a frame provided with two clamps having aligned cable seats, a drum rotatably mounted in said frame, coaxially with such cable seats, and a rotatable shaft borne by said frame and geared to said drum, the drum being rotatable in response to shaft rotation.

40 2. In a joint-building machine for electrical cables the combination of a frame provided with two clamps having aligned cable seats, and a drum rotatably mounted, coaxially with such cable seats, said drum consisting of opposite heads and connecting rods, and the heads of the drum being provided 45 with radially extending slots of a width as great as the cable seats of the aforesaid clamps.

50 3. In a joint-building machine for electrical cables the combination of a frame provided with two clamps having aligned cable seats, a drum rotatably mounted, coaxially with such cable seats, said drum consisting of opposite heads and connecting rods, and the heads of the drum being provided 55 with radially extending slots of a width as great as the cable seats of the aforesaid clamps, and removable closures for such slots, said removable closures being provided with 60 means for carrying rotatably a reel for sheet material.

65 4. In a joint-building machine for electrical cables the combination of a frame provided with clamps having aligned cable seats, a drum rotatably mounted, coaxially

with such cable seats, aligned bearings in the heads of said drum, and a reel for sheet material rotatably mounted in the said bearings.

5. In a joint-building machine for electrical cables the combination of a frame provided with clamps having aligned cable seats, a drum rotatably mounted, coaxially with such cable seats, a reel for sheet material rotatably mounted between the heads of 70 said drum, a rod extending between the heads of the drum adjacent such reel, a brake member extending from said rod, and means for securing said brake member against rotation on the rod axis. 80

6. In a joint-building machine for electrical cables the combination of a frame provided with clamps having aligned cable seats, a drum rotatably mounted, coaxially with such cable seats, a reel for sheet material rotatably mounted between the heads of 85 said drum, a rod extending between the heads of the drum adjacent such reel, a resilient finger extending from said rod, and adjustable means for securing said finger against rotation on the rod axis. 90

7. In a joint-forming machine for electrical cables the combination of a frame, two clamps borne by said frame and provided with aligned cable seats, a drum rotatably 105 mounted on said frame coaxially with such cable seats, said drum consisting of opposite heads and spacing rods, said rods being adjustable in their position radially with respect to said heads, and a reel for sheet material rotatably borne between the drum heads. 100

8. In a joint-forming machine for electrical cables the combination of a frame provided with clamps having aligned cable 105 seats, a drum rotatably mounted in said frame coaxially with said cable seats, a reel for sheet material rotatably mounted in said drum, and a knife borne by and adjustable longitudinally of said drum. 110

9. In a joint-forming machine for electrical cables the combination of a frame provided with clamps having aligned cable seats, a drum rotatably mounted in said frame coaxially with said cable seats, said 115 drum including opposite heads and a head-connecting rod, a reel for sheet material rotatably borne by said drum, a support borne by and movable longitudinally upon said rod, and a knife blade borne by said support and adjustable in a plane perpendicular to the axis of the structure. 120

10. In a joint-forming machine for electrical cables the combination of a frame provided with clamps having aligned cable 125 seats, a drum rotatably mounted in said frame coaxially with said cable seats, a reel for sheet material rotatably mounted in said drum, a knife borne by said drum and adjustable both axially and radially of the 130

drum, and a second knife also borne by said drum and adjustable longitudinally thereof.

11. In a joint-forming machine for electrical cables the combination of a frame provided with clamps having aligned cable seats, a drum borne by said frame and rotatable coaxially with such cable seats, a reel for sheet material rotatably borne by said drum, and a deflection-resisting abutment borne by said drum and extending adjacent an introduced cable body.

12. In a joint-forming machine for electrical cables the combination of a frame provided with clamps having aligned cable seats, a drum borne by said frame and rotatable coaxially with such cable seats, such drum including opposite heads and a head-connecting rod, a reel for sheet material rotatably borne by said drum and adapted to

deliver sheet material over said rod to a 20 cable body clamped to said seats, and an abutment borne by said drum and extending adjacent the position occupied by a cable body when clamped to said seats, said abutment being adjustable radially of an introduced cable body.

13. In a joint-building machine for electrical cables the combination of means for clamping the cable structure against rotation, a drum rotatably mounted coaxially 30 with such cable structure, and a shaft rotatable on an axis stationary with respect to the cable body and geared to said drum.

In testimony whereof we have hereunto set our hands.

DONALD M. SIMONS.
FRANK D. BARBOUR.
